(57) **CLAIM**

The ornamental design for a packaged terminal air conditioner as shown and described.

DESCRIPTION

FIG. 1 is a perspective view of a packaged terminal air conditioner according to a first embodiment;

FIG. 2 is a front view thereof;

FIG. 3 is a top view thereof;

FIG. 4 is a bottom view thereof;

FIG. 5 is a left view thereof; and

FIG. 6 is a right view thereof.

FIG. 7 is a perspective view of a packaged terminal air conditioner according to a second embodiment;

FIG. 8 is a front view thereof;

FIG. 9 is a top view thereof;

FIG. 10 is a bottom view thereof;

FIG. 11 is a left view thereof; and,

FIG. 12 is a right view thereof.

The broken lines shown in the figures depict features of the packaged terminal air conditioner that form no part of the claimed design.
